US00D528863S

(12) **United States Design Patent** (10) **Patent No.:** **US D528,863 S**
Hayes et al. (45) **Date of Patent:** **** Sep. 26, 2006**

(54) **CUP**

(75) Inventors: **Thomas J. Hayes**, McHenry, IL (US);
Ashwin N. Shah, Fairport, NY (US);
Jeff Wolcott, Grayslake, IL (US); **Jesse P. Carlson**, Bay Village, OH (US);
David K. Orr, Austin, TX (US);
Michael J. Maczuzak, Bratenahl, OH (US)

(73) Assignee: **Pactiv Corporation**, Lake Forest, IL (US)

(**) Term: **14 Years**

(21) Appl. No.: **29/240,857**

(22) Filed: **Oct. 18, 2005**

Related U.S. Application Data

(63) Continuation of application No. 11/069,794, filed on Mar. 1, 2005, which is a continuation-in-part of application No. 29/215,059, filed on Oct. 12, 2004.

(51) **LOC (8) Cl. 07-01**

(52) **U.S. Cl. D7/523; D7/532**

(58) **Field of Classification Search** .... D7/396.2, D7/396.1, 531, 532, 530, 509, 523, 510; 215/10, 12.1, 382, 384, 387, DIG. 7; D9/429, D9/556, 428, 42; D11/143, 153; 229/103.1, 229/403, 404, 400, 106; 426/86; 206/519, 206/520, 217, 503, 505, 515; 220/645, 671, 220/675, 592.17, 780, 608, 592.16, 70; 29/401.1
